C. W. BARNARD

DISPLAY PACKAGE AND SUPPORT THEREFOR

Filed Nov. 26, 1923

Inventor:
Charles W. Barnard,
By G. Hindahl, Parker & Carlson,
Attns.

UNITED STATES PATENT OFFICE.

CHARLES W. BARNARD, OF CHICAGO, ILLINOIS.

DISPLAY PACKAGE AND SUPPORT THEREFOR.

Application filed November 26, 1923. Serial No. 676,891.

To all whom it may concern:

Be it known that I, CHARLES W. BARNARD, a citizen of the United States, residing at Chicago, in the county of Cook and State 5 of Illinois, have invented a certain new and useful Display Package and Support Therefor, of which the following is a specification.

The invention relates to a package for an article or articles of merchandise, such 10 for example as medicinal tablets, candies in tablet forms, chewing gum, etc. Goods of this character require for their successful distribution and sale that they be brought before the buying public, and it is found 15 desirable for the retailer to display the goods in a conspicuous place so that the attention of the prospective purchaser shall be attracted thereto.

The primary object of my invention is 20 to produce a package for goods of the character indicated which will lend itself readily to such display purposes.

A further object is to render it possible 25 to carry a package of the goods on the person without an annoying rattle of the goods in the package when a portion of the contents thereof has been removed.

Another object is to provide a novel display device constituting a support upon 30 which a plurality of packages may be mounted for display purposes.

Figure 1 of the drawings is a perspective view of a plurality of packages constructed 35 in accordance with my invention, the packages being shown supported upon a suitable display device.

Fig. 2 is a perspective view of the lower or base portion of a two-piece container showing a series or row of tablets connected 40 together in edge to edge relation so as to fit within a continuous channel provided by the container.

Fig. 3 is a perspective view of the upper or cover portion of the container shown 45 in Fig. 2.

My improved package is constructed to provide a channel of a depth substantially equal to the thickness of the tablet to be contained therein, the inner wall of the 50 channel defining an aperture adapted to receive a supporting member of a display device; and the tablets are preferably connected together in edge to edge relation with weakened portions between them so that 55 when a portion of the contents of the package has been removed, the remaining tab-

lets shall be retained by the channel against movement, thus avoiding an objectionable rattling of the contents of the package when carried upon the person. 60

Usually packages for medicinal tablets and similar goods are made from tin or other sheet metal, and my improved package is herein shown as thus constructed of metal, being in the form of a two-piece box 65 or container. It will be apparent, however, that the invention is not limited to the use of sheet metal nor to the particular construction of the container herein shown.

The package when constructed in accordance with the present disclosure comprises 70 a lower or base portion 10 of a two piece container and a cover portion 11. Said base and cover portions are provided at their inner edges with upturned and downturned 75 flanges 12 and 13 respectively, and spaced inwardly a short distance from said outer flanges they are provided with corresponding flanges 14 and 15 which define a central aperture 16. Said flanges on the base 80 and cover sections are adapted to interfit or telescope as will be readily apparent.

There is thus formed between the inner and outer flanges a continuous channel 85 adapted to receive a series of tablets 17 arranged in edge to edge relation. Preferably the flanges are made of a width such that this channel is very shallow, being of a depth corresponding substantially to the thickness of the tablets. 90

The channel thus provided is adapted to hold the tablets against free movement in the package when a portion of the contents thereof has been removed. But preferably I utilize the channel to accomplish this result more effectually by connecting the tablets together in edge to edge relation. Thus referring to Fig. 2, I have shown the tablets 17 connected by intermediate portions or links 18 of a thickness less than the thickness 100 of the tablets so as to form a weakened dividing line or groove between the tablets facilitating their separation into individual units.

The package may obviously be made of 105 any desired shape while maintaining its flat form. Herein I have shown it in the form of a diamond and the central aperture therein is preferably similarly shaped.

As an illustration of the manner in which 110 my improved package may be conveniently displayed upon the counter of the retailer,

I have shown in Fig. 1 a display device comprising a suitable base 19 from which rises centrally thereof a supporting member in the form of standard 20 preferably shaped 5 to correspond with the shape of the central aperture in the package so that when a plurality of packages are placed over the standard as shown, they are maintained in a uniform position thereon.

10 Other forms of display devices adapted to utilize the central aperture in the package to receive a supporting member will doubtless occur to those skilled in the art.

I claim as my invention:

15 1. A package adapted for display purposes constructed to provide a relatively shallow channel, and a cover for the channel, the inner wall of said channel serving to define a hole through the package.

20 2. The combination of a display package constructed to provide a channel and a cover for the channel, the inner wall of said channel serving to define an aperture in the package and tablets connected together in 25 edge to edge relation and adapted to fit into the channel whereby the latter may serve to hold the tablets against movement in the package after a portion of its contents has been removed.

30 3. A container for tablets and the like comprising, in combination, a base member having an aperture therein, inner and outer

flanges extending up respectively from the outer edges of said base member and the edges of said aperture, a cover plate having a similar aperture adapted to be positioned in alignment with said first mentioned aperture, depending flanges on said cover plate at its outer edges and at the edges of its aperture, said flanges being adapted to telescope with the flanges on said base member to confine the tablets within the compartment defined by the spaced flanges, and said inner flanges serving to define an opening through the container.

4. The combination with a base having a standard rising therefrom and a display package, constructed to provide a channel and a cover therefor, the inner wall of said channel serving to define a hole through the package adapted to receive said standard.

5. A display package for tablets comprising a body constructed to provide a channel, and a cover for the body, said channel being adapted to receive tablets arranged in edge to edge relation and fitting in the channel whereby the latter may serve to hold the tablets against movement in the package after a portion of its contents has been removed.

In testimony whereof, I have hereunto affixed my signature.

CHARLES W. BARNARD.
